(57) **CLAIM**

The ornamental design for a notebook computer as shown and described.

DESCRIPTION

FIG. 1 is a rear top perspective view of a notebook computer showing our new design;

FIG. 2 is another rear top perspective view thereof;

FIG. 3 is a rear bottom perspective view thereof;

FIG. 4 is another rear bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a cross sectional view taken in the direction of line 11-11 in FIG. 6;

FIG. 12 is an enlarged view of the portion, labeled '12' in FIG. 2;

FIG. 13 is an enlarged view of the portion, labeled '13' in FIG. 3;

FIG. 14 is an enlarged view of the portion, labeled '14' in FIG. 6;

FIG. 15 is an enlarged view of the portion, labeled '15' in FIG. 7;

FIG. 16 is an enlarged view of the portion, labeled '16' in FIG. 8; and,

FIG. 17 is an enlarged view of the portion, labeled '17' in FIG. 11.

The evenly-dashed broken lines illustrate portions of the notebook computer that form no part of the claimed design. The dot-dash broken lines indicates cutoff boundaries for enlarged detail portion views and form no part of the claimed design. The dot-dot-dash broken line in FIG. 6 illustrates the cross-section line and form no part of the claimed design. Unshaded surfaces form no part of the claimed design.

1 Claim, 17 Drawing Sheets
